ATTYS.

UNITED STATES PATENT OFFICE.

WILLIAM C. TREGONING, OF CLEVELAND, OHIO, ASSIGNOR TO THE TREGONING ELECTRIC MANUFACTURING COMPANY, OF CLEVELAND, OHIO, A CORPORATION OF OHIO.

ELECTRIC CUT-OUT.

No. 890,200.

Specification of Letters Patent.

Patented June 9, 1908.

Application filed April 8, 1907. Serial No. 366,942.

To all whom it may concern:

Be it known that I, WILLIAM C. TREGONING, a citizen of the United States, residing at Cleveland, in the county of Cuyahoga and State of Ohio, have invented certain new and useful Improvements in Electric Cut-Outs, and do declare that the following is a full, clear, and exact description of the invention, which will enable others skilled in the art to which it appertains to make and use the same.

My invention relates to electric cut-outs and is an improvement comprising the combination and arrangement of parts substantially as hereinafter shown and described and more particularly pointed out in the claims.

As ordinarily, my device is in two main separable parts, and the object of the invention is to provide an interlocking arrangement between the contact members of the two parts, whereby both mechanical and electrical contact is made between a pair of members and the electrical contact is supplemented by the mechanical to protect the former against undue strain.

In the accompanying drawings, Figure 1 is a cross sectional view of the two separable rosette parts shown united. Fig. 2 is a face elevation of the base part, and Fig. 3 a similar view of the cap of the rosette. Fig. 4 is a perspective view of one of the interlocking contact members for the base, and Fig. 5 is a perspective view of one of the interlocking contact members for the cap. Fig. 6 is a sectional view of a portion of two rosette parts and illustrating a modification of the interlocking contact member for the base. Fig. 7 is a sectional detail and edge view of two contact members interlocked and as viewed if looking outward from line 7-7, Fig. 1, and Fig. 8 illustrates said parts apart and as entering into locking relation.

The general construction of the rosette or cut-out is not considered as embodying anything new over the usual forms of rosettes, except as hereinafter pointed out, and any separable arrangement may be used which comprises a base part —2— and a cap —3— removably mounted thereon, said parts, however, being preferably made of porcelain or other suitable insulating material. Both said parts are recessed or internally grooved at —4— and —5— respectively, and pro-

vided with screw openings and seats —6— 55 and —7—, respectively, for their respective interlocking contact members —8— and —9—. Openings —10— in base —2— are also provided for fastening screws (not shown) whereby said base may be attached 60 to a wall or ceiling, and cap —3— has a central recess and opening —11— through which the electrical cords are passed and connections made with the screw terminals within the cap, which also has provision for 65 fuses —12—, as usual.

Now coming to the new and novel features of the device, and as embodied in the interlocking contact members —8— and —9—, it will be seen that they are in pairs oppositely located on a diametrical line through the rosette and that the base contact members —8— comprise a stiff spring plate which may be bent into the angular form shown in Fig. 6, but which in the other 75 figures is shown as consisting of a flat body of —L— outline having screw holes —14— in one angle portion —15— whereby screws —16— secure the said member firmly in place upon the base with the other angle 80 portion —17— projecting inward over recess —4— on a plane substantially flush with the face of said base. Portion —17— is preferably curved at its edges to conform with the circular outline of the rosette, and has a slot 85 —18— centrally thereof which extends parallel with said edges from a point near the end edge —19— of said portion —17— to approximately the opposite edge —20— where it makes an abrupt angular turn in 90 the direction of portion 15 and then outward to the edges thereby providing a spring tongue —21— of L shape having its base of the same width at edge —20— as the opposite edge —19—. Each of said edges is 95 downturned to provide locking lips 22 as will hereinafter more fully appear. The free end of tongue —21— lies normally on an inclined plane in respect to the more rigid half —23— of portion —17—, as seen best in 100 Fig. 8, and said tongue becomes the main factor in making electrical contact with cap contact member —9—. Rigid part —23— supplements tongue —21— in making electrical contact, but its primary and important 105 function is to back up or brace said tongue against mechanical strain, such a strain for instance as would occur in separating cap 3

from base 2, or any pull thereon by the weight suspended from said cap if the device is remounted upon the ceiling.

The contact members —9— of cap —3— must necessarily be constructed with particular reference to contact portions 21 and 23 of member —8—, and to this end each comprises a **U** shaped member in cross section which is fastened to cap —3— by screws —24—. Each member —9— has a projecting body portion —25— of the same or approximately the same width as portion 17 of contact member 8, or in other words has a width corresponding to both spring 15 tongue 21 and rigid part 23, and whereby full engagement is made with both said parts for the purposes described. The free end —26— of body portion —25— is bent or inclined to provide both a lock and a guide 20 for spring tongue 21. Thus, when cap 3 is rotated to bring contact members —8— and —9— into locking relation tongue 21 engages the inclined face of end 26 and rides thereon into place. Interlocking between said members is brought about by locking lips 25 —22— of contact member —8—, and it will be noted that body portion —25— of member —9— is of less length than tongue —21— to fit snugly between said lips —22— (see 30 Fig. 7). The locking lip —22— at end —19— of member —8— serves as a stop to limit the rotation between the base and cap parts when putting them together.

The spring members 8 are of brass and 35 comparatively thick or heavy in cross section to make them strong and serviceable. But to provide a good elastic or flexible spring action said members are formed into a double spring by shaping a flat plate into 40 oppositely extending spring portions, the outer or freer spring tongue being a continuation of the inner and stiffer spring portion and which latter portion extends at right angles to the base or fastening part of 45 the member. It will also be understood that both spring portions lie on substantially the same plane and that one supplements the other, not only in spring action but also in making a better and stronger contact with 50 member —9— thus assuring greater mechanical strength. Both ends of the spring portions of members 8 have a greater width than the main or central stem of each portion, the object being to provide good and 55 sufficient contact surface for initial electrical contact and final break.

What I claim is:—

1. In electrical cut-outs, separable base and cap parts having electrical contact members adapted to interlock, one of said contact members consisting of a base part having a spring portion projecting therefrom and a secondary spring portion projected as a continuation thereof in an opposite direction on 65 the same plane and parallel thereto.

2. In electrical cut-outs, a base part and a cap part and interlocking electrical contact members separably uniting said parts, one of said contact members having a stiff backing spring extending from its base, and a free 70 spring integral with the free end of said backing spring and projecting therefrom on the same plane as a parallel extension thereof, and said other contact member having a face portion adapted to overlap and engage both 75 spring portions of said first contact member.

3. In electrical cut-outs, a base part and a cap part and interlocking electrical contact members separably uniting said parts, one of said contact members comprising a spring 80 plate having a split portion divided into oppositely extending spring tongues relatively as shown, and the other of said contact members adapted to overlap and engage both 85 spring tongues of said spring plate.

4. An electrical cut-out contact member comprising a metallic plate formed of one piece and having a base part, a spring extension at an angle to said base part, a secondary spring extension integral with said first extension and projecting from its free end parallel and substantially on the same plane therewith, and a lateral portion on the free end of said second extension, said member providing a double spring disposed in parallel 90 lines on the same plane and with their free ends relatively wider than their main stems. 95

5. In electrical cut-outs, a base part and a cap part and interlocking electrical contact members separably uniting said parts, one of said contact members comprising a flat base 100 plate of angular shape having a split portion divided into oppositely extending tongues with locking lips at their free ends, and the other of said contact members adapted to 105 overlap and engage both said tongues of said first contact member and having opposite end edges adapted to engage said lips.

6. An electrical cut-out contact member comprising a spring plate having a base part 110 and a stiff spring portion extending therefrom, and being further provided with secondary spring portion integral with the free end of said first portion and projected therefrom as a free spring in an opposite direction 115 and parallel therewith.

7. A contact member for electrical cut-outs comprising a spring plate having a split portion divided into oppositely extending spring tongues relatively as shown. 120

8. A contact member for electrical cut-outs comprising a base plate of substantially **L** shape having a split portion divided into oppositely extending spring tongues with locking lips at their free ends. 125

9. A contact member for electrical cut-outs comprising a base plate having a stiff spring extension provided with a reversely extending spring portion at the free end thereof and on substantially the same plane 130

therewith said portion having a free end of greater width than its stem projecting toward the base end of said member.

10. A contact member for electrical cutouts comprising a base plate of spring metal having a stiff spring portion provided with a supplemental spring tongue of L shape.

In testimony whereof I sign this specification in the presence of two witnesses.

WILLIAM C. TREGONING.
